Attorney, Agent, or Firm—Helfgott & Karas, P.C.

[57] **CLAIM**

The ornamental design for a wobbling cat toy, as shown and described.

DESCRIPTION

FIG. 1 is a perspective view of the wobbling cat toy showing the new design;

FIG. 2 is a left side view thereof;

FIG. 3 is a back view thereof;

FIG. 4 is a top plan view thereof;

FIG. 5 is a right side view thereof;

FIG. 6 is a bottom plan view thereof; and,

FIG. 7 is second embodiment of FIG. 1, the difference being in the absence of the feathered portion.

1 Claim, 4 Drawing Sheets

FIG. 1

FIG.3

FIG.2

FIG. 5

FIG. 4

FIG. 6

FIG. 7

UNITED STATES PATENT AND TRADEMARK OFFICE
CERTIFICATE OF CORRECTION

PATENT NO. : Des. 426,036
DATED : May 30, 2000
INVENTOR(S) : Jonathan Willinger, et al.

Page 1 of 1

It is certified that error appears in the above-identified patent and that said Letters Patent is hereby corrected as shown below:

Please change item 75 from Vincent Balera to Vincent Baiera.

Signed and Sealed this
Third Day of July, 2001
